Des. 218,494
Patented Aug. 18, 1970

218,494

COAT HANGER

Henry S. Leichter, 225 W. Lehigh Ave.,
Philadelphia, Pa. 19133

Filed May 8, 1969, Ser. No. 17,063

Term of patent 14 years

Int. Cl. D6—07

U.S. Cl. D80—8

Fig 2

Fig 3

Fig 4

Fig 5

FIG. 1 is a side elevational view of a coat hanger embodying my new design;

FIG. 2 is an elevational view taken from the side opposite that shown in FIG. 1;

FIG. 3 is a fragmentary elevational view taken from one end thereof, the hook portion being broken away for convenience of illustration.

FIG. 4 is a top plan view thereof.

FIG. 5 is a bottom plan view thereof.

What I claim is:

The ornamental design for a coat hanger, as shown.
